UNITED STATES PATENT OFFICE.

EDWIN S. PILLSBURY AND EDWARD BRETCH, OF ST. LOUIS, MISSOURI,
ASSIGNORS TO THE H. E. LINDSEY ELECTRICAL SUPPLY COMPANY,
OF ST. LOUIS, MISSOURI, A CORPORATION OF MISSOURI.

MOTOR.

SPECIFICATION forming part of Letters Patent No. 770,922, dated September 27, 1904.

Application filed April 17, 1903. Serial No. 153,071. (No model.)

To all whom it may concern:

Be it known that we, EDWIN S. PILLSBURY and EDWARD BRETCH, citizens of the United States, residing at St. Louis, Missouri, have invented a certain new and useful Improvement in Motors, of which the following is a full, clear, and exact description, such as will enable others skilled in the art to which it appertains to make and use the same, reference being had to the accompanying drawings, forming part of this specification, in which—

Figure 1 is a central vertical sectional elevation. Fig. 2 is a top view, partly in section; and Figs. 3 and 4 are diagrammatic views, Fig. 3 showing the pole-pieces upon the stationary member, and Fig. 4 showing the pole-pieces upon the rotatable member.

Our invention relates to improvements in motors, and more particularly to electric motors, our object being primarily to provide simple and efficient means for starting the rotatable element.

A further object is to provide a structure which has two motors adapted to act upon the same movable part, and to combine with these motors means whereby power can be first supplied to one of them and then after the said movable part has been properly started power can be cut off from the motor which was initially energized and supplied to the second motor.

To these ends and also to improve generally upon devices of the character indicated, our invention consists in the various matters hereinafter described and claimed.

Although it will be readily understood that the present invention is in no wise limited to such use, we have herein illustrated the invention in connection with a ceiling-fan, the general construction of such fan and what may be termed the "main" or "working" motor (as distinguished from the hereinafter-referred-to auxiliary or starting motor) being of the character fully disclosed in patent to Edwin S. Pillsbury upon electric motors, No. 642,364, granted January 30, 1900.

Referring now more particularly to the drawings, A indicates a frame-plate which in

the present embodiment of our invention is adapted to be suspended from the ceiling, as 50 by connection with the supporting-pipe A', and C is a shaft fixed upon and depending from said frame-plate, a bell-shaped oil-cup D surrounding the lower end of said shaft C and being conveniently supported from said 55 shaft. The armature frame or spider E is provided with a hub portion e, which is sleeved upon the before-mentioned shaft C, said armature frame or spider being the movable or rotatable element of the present construction and having suitable sockets K, adapted to receive the shanks of the fan-blades. Mounted upon the periphery of the frame-plate A is the field-magnet core B of the main or working motor, and suitably supported 60 upon the armature-frame E and in position to properly coöperate with the said field-magnet core is the armature M of said main or working magnet. The wire 1 is wound about the polar projections of the field-magnet core and 65 has its ends connected to a suitable source of electric energy. This much of the construction of the present device is substantially similar to the construction illustrated in the before-mentioned patent of Pillsbury, and will 70 therefore not be specifically described in this specification, it being understood that when energy is supplied to the field B and the rotating armature is started the said main or working motor causes the rotatable element or armature-frame E to continue to rotate.

The present invention relates more particularly to means for starting the movement of the before-mentioned rotatable element or armature-frame E. Suitably mounted upon the 85 hub 10, which is fixedly connected to and depends from said stationary frame-plate A, are commutator-segments 11 and 11^a, here shown as substantially semicircular and as two in number, these segments being out of electrical connection with each other, and there being preferably insulation 12 between the ends of the segments and between the segments and their supporting-hub. Depending 90 from the before-mentioned stationary frame-plate A and intermediate the before-mentioned

central hub 10 and the before-mentioned peripherally-supported main field B are segmental cores or polar projections 13 and 13^a, which are oppositely wound by the wires 14 and 14^a, respectively, each of said wires having one end connected to the before-mentioned main winding-wire 1 and its other end connected to one of the before-mentioned commutator-segments. Thus it will be apparent that if the said commutator-segments are electrically connected and current is permitted to flow from the source of electrical energy the cores 13 and 13^a become magnets of opposite polarity.

Rising from the rotatable member or armature-frame E are cores or polar projections, which are adapted to coöperate with the before-mentioned field-cores 13 and 13^a, and are spaced substantially equal distances from each other. Three such armature-cores are here shown and are indicated, respectively, 15, 15^a, and 15^b. Mounted upon said armature-frame E are radially-disposed casings 16, which have their inner ends open, and each of these casings is electrically connected to the winding-wire 17 of one of the said armature-cores, each of these cores being wound in the same direction and the winding-wires being connected to each other, as shown at 17^a.

Slidably supported in each casing 16 is a weighted brush 18, between whose outer end and the outer wall of the casing is interposed the spring 19, which exerts its force to move the brush inwardly and in engagement with one of the before-mentioned commutator-segments 11 11^a. When the rotatable frame E is at rest or is rotating slowly, the springs 19 serve to hold the brushes in contact with the commutator-segments; but when said rotatable frame attains a certain speed said brushes are, by centrifugal action, thrown outwardly against the force of the said springs 19, and are thus moved out of contact with the said commutator-segments.

Referring now more particularly to the diagrams Figs. 3 and 4, it will be seen that when the current is supplied it flows from the source of energy to the positive side of the main winding-wire 1, from such side of said main winding-wire through the wire 14 about the field-core 13, thus making said core a positive pole; thence flows to the commutator-segment 11, thence to the brush 18 connected to the winding of the armature-pole 15, thence through the common connecting-point 17^a to the others of said armature-poles, whereby in the position of the parts shown in Figs. 3 and 4 the armature-core 15^a becomes a magnet of negative polarity and the armature-core 15^b is not energized, by reason of the fact that its coöoperating brush is upon the insulation between the commutator-segments. From the winding about the core 15^a the current flows from its connected brush to the commutator-segment 11^a, thence about the

field-core 13^a, whereby said core becomes a magnet of negative polarity, and thence to the negative side of the main winding-wire 1, the current flowing from this point back to the source of energy. Under such circumstances the positive field-core 13 will attract the negative armature-core 15^a and will repel the positive armature-core 15, thus causing the rotatable element E, upon which the armature-cores 15, 15^a, and 15^b are carried, to commence to rotate, and as the brush coöperating with the armature-core 15^b enters upon the segment 11^a said armature-core 15^b becomes a south pole, and having passed the center of the field-core 13^a said armature-pole 15^b is repelled by the negative field-pole 13^a, the armature-pole 15^a becoming dead as it reaches the center of the positive field-pole (by reason of the fact that the brush coöperating with said armature-pole 15^a contacts with the insulation between the commutator-segments when said armature-pole reaches such central position under the positive field-pole) and the armature-pole 15 becoming a negative pole when it enters upon the commutator-segment 11^a. It is believed that the changes in polarity of the armature-cores during the rotation of said armature will be fully understood without further explanation. After the rotatable armature-carrying frame E attains proper speed the brushes 18 move out of contact with the commutator-segments 11 and 11^a, whereupon the auxiliary or starting motor is thrown out of circuit and the whole current flows into the field B of the main or working motor, which main or working motor causes the rotatable element to continue to rotate in a manner which will be well understood. Thus by a very simple construction we are enabled to start the operation of an induction-motor and to cut out the starting mechanism after the main motor is in proper condition to operate.

Oil from the cup D creeps up between the stationary shaft C and the hub or sleeve e³ of the rotatable armature-frame. The upper end of said sleeve e³ is spaced from the field-magnet frame-plate A above it to produce an oil-passage e at the top of said sleeve, and the hub 10, carried by the said field-magnet frame-plate, encircles the said sleeve e³ and is spaced therefrom to produce an oil-passage e''. Thus oil which creeps up between the said shaft C and the sleeve e³ passes into the passage e and thence down the passage e'' back to the oil-cup, the said hub 10 coöperating with the said sleeve e³ to produce this passage e'' and preventing the oil from being thrown off the rotating sleeve e³ by centrifugal action.

The armature M is of what is commonly known as the "squirrel-cage" type, and includes the induced current-conducting bars N and the short-circuiting rings O, as in the before-mentioned patent to Pillsbury, the core of said armature being upon the outer side of

said bars N. In the present construction the said bars are provided with notches 20 upon their inner sides, and the said rings O, one above and the other below the core-laminations of the armature, are simply slipped into said notches. Thus the said rings are securely held upon the said bars, the resiliency of the rings tending to force the bars outwardly against the core, and the laminations are securely held between the rings. Because of the construction just described the squirrel-cage armature can be quickly and conveniently assembled, the parts being properly held together by themselves alone before the armature is dipped in solder.

We are aware that many minor changes in the construction, arrangement, and combination of the several parts of our device can be made and substituted for those herein shown and described without in the least departing from the nature and principle of our invention.

Having thus described our invention, what we claim as new, and desire to secure by Letters Patent, is—

1. The combination with a driven element, a source of electrical energy, and a main, induction-motor incapable of being started by energy supplied to it from said source, said motor being in driving connection with said driven element and in electrical connection with said source of energy, of means for starting said motor and comprising an auxiliary, conduction-motor capable of being started by energy supplied to it from said source, said auxiliary motor being in driving connection with said driven element and in electrical connection with said same source of energy, and means whereby after said main, induction-motor has been started energy is cut off from said auxiliary, conduction-motor; substantially as described.

2. The combination with a driven element, and a source of electrical energy, of a main motor, an auxiliary motor, each of said motors having as elements a field and an armature, one of said motor elements of each of said motors being in driving connection with said driven element, a contact member, a brush co-operating with said contact member and electrically connected to one of said motor elements of said auxiliary motor, a circuit including said source of energy and one of said motor elements of said main motor, a circuit including said source of energy, said contact member, said brush, and said auxiliary motor element to which said brush is electrically connected, and means whereby said brush is electrically disconnected from said contact member when said main motor has been rendered operative; substantially as described.

3. The combination with a movable element, of two armatures thereon, a main field co-operating with one of said armatures, a starting field co-operating with the other of said arma-

tures, a contact member, a brush co-operating with said contact member and electrically connected to said second-mentioned armature, a source of electrical energy, a circuit including said source of energy and said main field, a circuit including said source of energy, said starting field, said contact member, said brush, and said second-mentioned armature, and means whereby said brush is electrically disconnected from said contact member when said main field and its co-operating armature have been rendered operative; substantially as described.

4. The combination with a relatively fixed frame-plate, of a rotatable frame-plate, a main stator upon said fixed frame-plate, a co-operating rotor upon said rotatable plate, cores projecting from said main plate and provided with stator-windings, and co-operating cores projecting from said rotatable plate and provided with rotor-windings; substantially as described.

5. The combination with a relatively fixed frame-plate, a rotatable frame-plate, a main field upon said fixed frame-plate, a co-operating armature upon said rotatable plate, cores projecting from said main plate and provided with field-windings, and co-operating cores projecting from said rotatable plate and provided with armature-windings; substantially as described.

6. The combination with a relatively fixed plate, of a rotatable plate, a motor having as elements a stator and a rotor, said stator being upon said fixed plate and said rotor being upon said rotatable plate, a relatively fixed contact member, a source of electrical supply, electrical connection between said source of supply and said contact member, a brush carried by said rotatable plate and co-operating with said contact member, said brush being adapted to be thrown from engagement with said contact member by centrifugal action, electrical connection between said brush and one pole of one of said motor elements, and electrical connection between the other pole of said one of said motor elements and said source of supply; substantially as described.

7. The combination with a relatively fixed plate, of a rotatable plate, a stator upon said fixed plate, a co-operating rotor upon said rotatable plate, a relatively fixed contact member, a source of electrical supply, electrical connection between said source of supply and said contact member, a brush carried by said rotatable plate and co-operating with said contact member, said brush being adapted to be thrown from engagement with said contact member by centrifugal action, electrical connection between said brush and one pole of said rotor, and electrical connection between the other pole of said rotor and said source of supply; substantially as described.

8. The combination with a relatively fixed frame-plate, a hub thereon, a commutator

- upon said hub and comprising electrically-disconnected segments, and a stator-motor element upon said plate and comprising opposite poles which are respectively electrically connected to different said contact-segments of said commutator, of a rotatable plate, a rotor-motor element thereon coöperating with said stator, a brush carried by said rotatable plate, coöperating with said commutator and electrically connected to one pole of one of said motor elements, said brush being adapted to be moved out of contact with said commutator by centrifugal force, and means whereby when said brush contacts with one of said commutator-segments electrical connection is made between the other of said commutator-segments and the other pole of said motor element in connection with said brush; substantially as described.
9. The combination with a relatively fixed plate, of stator-cores thereon, windings about said cores, a hub upon said plate, a commutator upon said hub and electrically connected to said windings, a rotatable plate, a plurality of rotor-cores upon said rotatable plate, windings about said cores, and brushes upon said rotatable plate and alternating with said rotor-cores, said respective brushes being electrically connected with said respective rotor-cores, coöperating with said commutator, and being adapted to be thrown from engagement with said commutator by centrifugal force; substantially as described.
10. The combination with a relatively fixed plate, of field-cores thereon, windings about said cores, a hub upon said plate, a commutator upon said hub and electrically connected to said windings, a rotatable plate, a plurality of armature-cores upon said rotatable plate, windings about said cores, and brushes upon said rotatable plate and alternating with said armature-cores, said respective brushes being electrically connected with said respective armature-cores, coöperating with said commutator, and being adapted to be thrown from engagement with said commutator by centrifugal force; substantially as described.
11. In a motor of the character indicated, the combination with a stator, a commutator comprising electrically - disconnected segments, a source of electrical supply, and electrical connection between the respective poles of said source of supply and said respective segments, of a rotatable plate, rotor-cores thereon, windings about said cores, radially-disposed casings upon said plate and alternating with said cores, brushes in said casings and respectively electrically connected to one pole of the respective said windings, said brushes being adapted to be moved by centrifugal force, springs in said casings serving to hold said brushes in engagement with said

commutator, and means whereby when a brush is upon one of said segments the opposite pole of the said winding to which said brush is connected is electrically connected to the other of said segments; substantially as described.

12. In a motor having as elements a stator and a rotor, two cores embodied in one of said motor elements, means for rendering said cores of opposite polarity, two electrically-disconnected commutator-segments, one of said segments being electrically connected to each of said before-recited cores, three similarly wound cores embodied in the other of said motor elements, similar ends of said windings being electrically connected together, and a brush for each of said last-mentioned three cores and electrically connected to the winding of its respective said core, said brushes coöperating with said commutator-segments; substantially as described.

13. The combination with two field-cores, of means for rendering said cores of opposite polarity, two electrically-disconnected commutator-segments, one of said segments being electrically connected to each of said field-cores, three armature-cores similarly wound, similar ends of said windings being electrically connected together, and a brush for each of said armature-cores and electrically connected to the winding of its respective said core, said brushes coöperating with said commutator-segments; substantially as described.

14. In a motor or the like, a frame-plate, a shaft depending therefrom, an oil-cup in which the lower end of said shaft is received, an armature-frame, a sleeve thereon about said shaft and also having its lower end extending into said oil-cup, there being an oil-passage at the upper end of said sleeve, a hub also depending from said frame-plate, said hub encircling said sleeve and being spaced therefrom to produce an oil-passage communicating between said first-mentioned oil-passage and said oil-cup, a commutator upon said sleeve, and a brush upon said armature-frame coöperating with said commutator; substantially as described.

15. In an armature or the like, a core, a series of bars extending transversely through the same and provided with lateral recesses upon one side above and below said core, and rings which are received in said recesses above and below said core; substantially as described.

In testimony whereof we hereunto affix our signatures, in the presence of two witnesses, this 11th day of April, 1903.

EDWIN S. PILLSBURY.
EDWARD BRETCH.
